UNITED STATES PATENT OFFICE

109,030

DESIGN FOR A VENDING MACHINE CABINET

Walter A. Tratsch, Chicago, Ill.

Application January 27, 1938, Serial No. 74,603

Term of patent 3½ years

To all whom it may concern:

Be it known that I, Walter A. Tratsch, a citizen of the United States and a resident of Chicago, in the county of Cook and State of Illinois, have invented a new, original, and ornamental Design for a Vending Machine Cabinet, of which the following is a specification, reference being had to the accompanying drawing, forming a part thereof, and in which:

The single figure is a perspective view of a vending machine cabinet showing my new design. The side walls are identical in appearance.

I claim:

The ornamental design for a vending machine cabinet, as shown and described.

WALTER A. TRATSCH.
